ABSTRACT: Detergent compositions which contain compounds bearing one or more sulphydryl radicals as activators for enzymes which themselves do not contain sulphydryl groups or disulfide bonds.

DETERGENT COMPOSITION

BACKGROUND OF THE INVENTION

1. Field of the Invention

This invention pertains to detergent compositions which contain compounds bearing one or more sulphydryl radicals as activators for enzymes which themselves do not contain sulphydryl groups or disulfide bonds.

2. Prior Art

It is known that proteolytic enzymes which do contain sulphydryl groups or disulfide bonds are reactivatable by adding a suitable reducing agent. So, e.g., it is known from U.S. Pat. No. 3,019,171 that cysteine and sodium thiosulfate are satisfactory for the activation of proteolytic enzymes containing sulphydryl groups or disulfide bonds. "Proteolytic enzymes" as meant in this patent are represented by vegetable enzymes such as pinguinain, papain, ficin, bromelin, bromelain, and a-cleplain. From French patent No. 765,063 it is known that activated protease can be used in detergent compositions; the activation is attained through the addition of hydrogen sulfide, thiosulfate or cyanic acid. The proteases utilized are of vegetable origin and also contain sulphydryl groups or disulfide bonds. Similar disclosures are found in British patent No. 475,880 which refers to detergent compositions containing vegetable enzymes which are reactivatable through the addition of sodium sulfides or polysulfides.

All these prior art references, however, teach that the proteolytic activity of enzymatic detergent compositions can be enhanced through the addition of activators which must be reducing agents. The reason for this is that the enzyme preparations to which these teachings apply are mostly represented by vegetable enzymes and more particularly by papain or its equivalents which, for a long time, were known to be reactivatable by a treatment with a reducing agent. Without being bound to any theory, it is assumed that this enhancement of papainlike enzyme preparations is related specifically to the changes of the oxidative state of the sulfur atoms which are present in the enzyme molecules. So for example, the activity of papain, which has decreased during its manufacture as a result of the oxidation of the active moiety containing cysteine, can be reactivated by an electrolytic reduction or by the addition of reducing agents.

THE INVENTION

It has now unexpectedly been found that a marked enzymatic activity enhancement is obtained by the use of detergent compositions with a content of surface-active agents, builders and enzymes, characterized in, that they contain:

from about 0.01 to about 10 percent by weight of a compound containing one or more sulphydryl groups, and from about 0.005 to about 4 percent by weight of enzymes which do not contain sulphydryl groups or disulfide bonds.

This is so much the more surprising as enzymes which do not contain sulphydryl groups or disulfide bonds are neither readily oxidizable nor reducible. Enzymes encompassed within the scope of this invention can contain sulfur in a form which does not respond readily to an oxidative or reductive treatment as taught in the prior art. An example of this is ALCALASE bearing a methionine rest which is not likely to be reactivated when submitted to a prior art treatment. The enhancing agents suitable for being incorporated into enzyme containing detergent compositions in accordance with this invention have to bear one or more sulphydryl groups. They can be substituted by inorganic or organic radicals or by a mixture of both, although, those derived from organic radicals are preferred for various reasons. Among the advantages one can enumerate for the enhancing agents of this invention are their improved odor acceptance and/or solubility relative to e.g., alkali-, earth-alkali or metal sulfides or polysulfides which are therefore less desirable in detergent compositions.

The enzymatic activity enhancement can be obtained with all commonly known sulphydryl bearing compounds. The

preferred activators within the scope of this invention are: cysteine hydrochloride, thioglycolic acid esters derived from C_{10-18} fatty alcohols, calcium-thio-glycolate and their equivalents; the particularly preferred activators are: cysteine, thioglycolic acid, thioglycolic acid esters derived from mC_1-C_8 alcohols, thioglycerol, and their equivalents. The activator should preferably be incorporated in an amount from about 0.01 to about 10 percent by weight, calculated on the total detergent composition. The preferred usage range is from about 0.05 weight percent to about 5 weight percent and most preferably from about 0.2 to about 2 weight percent. The enzymatic activity enhancement is not noticeable when less than 0.01 weight percent are incorporated into the detergent formulation while no additional activity synergism can be obtained by adding more than 10 weight percent of the activator compound. The enzymes suitable for use should not contain sulphydryl groups or disulfide bonds. They can be of any origin although these enzymes are mostly of bacterial origin. Most of the enzymes of vegetal origin do bear sulphydryl groups and/or disulfide bonds, e.g., papain. Preferred for use in the detergent compositions of this invention are the enzyme preparations commercially available under the trade names of "ALCALASE," manufactured by Novo Industry A/S, Copenhagen, Denmark and "DA-10," manufactured by Monsanto Chemical Company. ALCALASE is described, in a trade bulletin bearing that name which was published by Novo Industry A/S, as a proteolytic enzyme preparation manufactured by submerged fermentation of a special strain of *bacillus subtilis*.

Similar results are obtained in using any of the following enzyme preparations:

35	Trade Name	Manufacturer
	Protease ATP 360	Societe Rapide
		Seclin, France
40	Muxatase 221S	KNGSF
		Delft-Holland
	Thermouse PS 100	Soc. Belge Masubeni—Lida Sprl.
		Bruxelles, Belgium

Experimental enzymes from, for example, *Arthrobacter* sources have also shown similar enhancement with compounds containing one or more sulphydryl radicals when incorporated into detergent formulations.

The active enzyme is to be used in a quantity of from about 0.005 weight percent to about 4 percent by weight of the composition. Preferred is a quantity of enzymes of from about 0.01 to about 0.02 weight percent.

In addition to the enzymes and the activator, the detergent compositions of this invention can contain the usual mixtures of other ingredients which are currently incorporated into detergent compositions. So, e.g., organic detergents, builders, suds depressors, antiflocculating agents, brighteners, dyes, perfumes and so on can be used.

Examples of suitable detergent compounds for being employed in accordance with the present invention include:

60 —water-soluble soaps such as the sodium, potassium, ammonium and alkanolammonium salts of higher fatty acids (C_{10-C_2}) and, particularly sodium and potassium tallow and coconut soaps.

65 —anionic synthetic non-soap detergents being represented by the water-soluble salts of organic, sulfuric acid reaction products having in their molecular structure an alkyl radical containing from about eight to about 22 carbon atoms and a radical selected from the group consisting of sulfonic acid and sulfuric acid ester radicals. Examples of these are the sodium or potassium alkyl sulfates of alcohols derived from tallow or coconut oil; straight or branched chain sodium or potassium alkyl benzene sulfonates, sodium alkyl glyceryl ether sulfonates, sodium coconut oil fatty acid monoglyceride sulfates and sulfonates; sodium or potassium salts of sulfuric acid esters

of the reaction product of 1 mole of a higher fatty alcohol and about 1 to 6 moles of ethylene oxide; sodium or potassium alkyl phenol ethylene oxide ether sulfates with 1 to 10 units of ethylene oxide per molecule and wherein the alkyl radicals contain from eight to 12 carbon atoms; the reaction product of fatty acids esterified with isethionic acid and neutralized with sodium hydroxide; sodium or potassium salts of fatty acid amide of a methyl tauride, for example, are derived from coconut oil; sodium and potassium salts of SO_3 -sulfonated C_{10} - C_{24} α -olefins.

—nonionic synthetic detergents suitable for being used are, e.g., the condensation products of alkylene oxide with an organic hydrophobic compound, higher fatty amides and nonionic detergents having semipolar characteristics. Some examples of these nonionic detergents are defined hereafter:

1. One class of nonionic synthetic detergents is marketed under the tradename of "PLURONIC;" they are formed by condensing ethylene oxide with a hydrophobic base formed by the condensation of propylene oxide with propylene glycol.
2. Alkylphenol-polyethylene oxide condensates, being condensation products of alkyl phenols with 5 to 25 moles of ethylene oxide per mole of alkyl phenol.
3. The condensation product of ethylene oxide with the product resulting from the reaction of propylene oxide and ethylene diamine.
4. Condensation products of aliphatic alcohols with 5 to 30 moles of ethylene oxide per mole of alcohol.
5. The ammonia, monoethanol, and diethanol amides of fatty acids.
6. Long chain tertiary amine oxides such as dimethyl-dodecylamine oxide and bis-(2-hydroxyethyl)-dodecylamine oxide.
7. Long chain tertiary phosphine oxides such as dimethyl-dodecylphosphine oxide and dimethyl-(2-hydroxydodecyl) phosphine oxide.
8. Long chain sulfoxides such as dodecyl methyl sulfoxide and 3-hydroxy tridecyl methyl sulfoxide.

—Examples of ampholytic synthetic detergents: sodium-3-dodecylaminopropionate and sodium-3-dodecylamino-propane sulfonate.

—Zwitterionic synthetic detergents are for example 3-(N,N-dimethyl-N-hexadecylammonio) propane-1-sulfonate and 3-(N,N-dimethyl-N-hexadecylammonio)-2-hydroxy propane-1-sulfonate.

Suitable organic detergents include sodium alkyl benzene sulfonate, sodium alkyl sulfate, and mixtures thereof wherein the alkyl group is of branched or straight chain configuration and contains about 10 to about 18 carbon atoms.

The alkaline builder salts which can be employed in the detergent compositions of the present invention are employed in an amount to provide, for example, a weight ratio of alkaline builder salt to organic detergent of about 20:1 to 1:5. These builders can be selected from a wide variety of known inorganic or organic builder salts. Suitable alkaline, inorganic builder salts include the alkali metal carbonates, phosphates, polyphosphates and silicates.

Suitable organic builder salts include the alkali metal, ammonium, and substituted ammonium polyphosphonates, polyacetates, and polycarboxylates.

The polyphosphonates can be represented by the sodium and potassium salts of methylene diphosphonic acid-, ethylene diphosphonic acid-, ethane-1-hydroxy-1,1-diphosphonic acid and of ethane-1,1,2-triphosphonic acid. Also suitable are the water-soluble salts of ethane-2-carboxy-1,1-diphosphonic acid, hydroxymethanediphosphonic acid, carboxyl-diphosphonic acid, ethane-1-hydroxy-1,1,2-triphosphonic acid, ethane-2-hydroxy-1,1,2-triphosphonic acid, propane-1,1,3,3-tetraphosphonic acid, propane-1,1,2,3-tetraphosphonic acid, and propane-1,2,2,3-tetraphosphonic acid.

Some examples of polyacetate builders suitable for use herein include the water-soluble salts of ethylenediaminetetra-acetic acid, N-(2-hydroxyethyl)-ethylenediaminetriacetic acid, N-(2-hydroxyethyl)-nitrilodiacetic acid, diethylenetriaminepentacetic acid, 1,2-diaminocyclohex-anetetracetic acid and nitrilotriacetic acid. The trisodium salts of the above acids are preferably utilized.

The polycarboxylate builder salts suitable for use herein consist of water-soluble salts of polymeric aliphatic polycarboxylic acids as described in U.S. Pat. No. 3,308,067 which is incorporated herein by reference.

Bleaching compounds should preferably not be used in compositions in accordance with this invention, as there would certainly be a direct interference between the sulphydryl bearing compounds and the bleaching compounds resulting in a deterioration of the activators before they are able to enhance the enzymatic activity. Bleaching compounds can be added, however, provided they are physically protected from contact with the other ingredients of the detergent composition and particularly from being in contact with the activators. This is possible if they, as an example, are contained in hermetically sealed packages whose walls are made of a material which is only soluble in the laundering solution at a temperature exceeding about 65° C. as they will not interfere with the enzymatic activity enhancement which occurs in a temperature range from about ambient temperature to about 65° C. above which latter temperature the enzymes tend to be deteriorated by heat. Obviously, the same result can be attained when the bleach compounds are coated with a thin-coating of an inert water-soluble material which does not dissolve at a temperature of below 65° C.

The sulphydryl bearing activators can be incorporated into detergent compositions by any of the techniques known to be satisfactory for this purpose. Examples of the various possibilities which might be applied satisfactorily are enumerated in what follows:

The activators can, as such, or being encapsulated, be dry-mixed with the finished detergent composition. Obviously, the encapsulation seems to be in order in the event the sulphydryl bearing compound is represented by a liquid material which is likely to cause lumping to a solid detergent composition and also when the activator (solid or liquid) tends to lose its activity, due to oxidation or for other reasons during a prolonged storage. The encapsulating material should be neutral versus the activator, provide an adequately closed coating and also dissolve in aqueous laundering solutions at ambient temperature. Another possibility of incorporating the activators would be in preparing coagglomerates by spraying water onto mixtures of hydratable carrier with the activator alone or in mixture with the enzymes. Acceptable results are also obtained in spraying a solution of activators on a carrier, or a previously prepared agglomerate of the enzyme and the carrier as described in Belgian patent No. 697,481. It is quite obvious that this latter technique would work as well when a solution containing both the activator and the enzyme are sprayed on the hydratable carrier. The carriers suitable for being utilized should be compatible with the enhancing agents, particularly with respect to storage stability of the activator. Any of these techniques is suitable for preparing the detergent compositions referred to in the examples.

The unexpected enzymatic activity increase resulting from the incorporation of the sulphydryl containing activators into detergent compositions containing enzymes free of disulfide bonds and sulphydryl radicals is illustrated by a series of examples.

EXAMPLE I

Detergent compositions (a) and (b) having the compositions as indicated hereafter are prepared by conventional spray-drying of all ingredients but the enzyme carrier agglomerate. The latter is prepared separately by spraying a suspension or a solution of the enzyme preparation onto sodi-

um tripolyphosphate, thereby using the technique described in French Pat. No. 1,520,262, and admixed afterwards. The sulfhydryl containing activators are dry mixed with the finished detergent composition.

Ingredient	a (in weight percent)	b

¹ Anons, Journ. Gen. Physiol. 22, 79 (1939).

² Indicated with corresponding stain removal results.

³ Balance to 100.

These detergent formulations are used for preparing soaking and laundering solutions with a

0.5 percent product concentration

a water hardness of 20 grains/U.S. gallon.

Test swatches (cotton) stained with any of the following staining solutions are used for evaluations purposes:

blood-ink-milk

milk-ink

egg-white-ink

-cocoa

The blood-ink-milk (Art. 116) and cocoa (Art 112) swatches are supplied by EMPA, St. Gallen, Switzerland. The milk-ink and egg-white-ink staining solutions are prepared by adding a 15 percent aqueous solution of egg-white or milk (powdered or crystalline to a 15 percent aqueous solution of black drawing ink).

The swatches are immersed in the solution and passed through a handringer whererafter they are heated for 20 minutes in 70°C. water.

The test swatches are then soaked and/or washed thereby proceeding as follows:

A. The stained swatches are washed for 30 minutes at 45°

C. in a washing solution containing the enzymatic detergent composition and the activator. The operation is carried out in a "Launder-ometer" supplied by Atlas Electric Devices Co., Chicago, Illinois, U.S.A.; or in a "Terg-O-Tometer" supplied by U.S. Testing company, Hoboken, N.J., U.S.A.

B. The stained swatches are soaked at ambient temperature for 2 hours in a soaking solution, containing the enzymatic detergent composition and the activator, whererafter the swatches to be soaked are agitated for 10 minutes.

The stain removal resulting from the soaking and washing tests, as described hereabove, are each time compared to the stain removal resulting from identical tests carried out in the absence of an activator for the enzymatic activity.

The stain removal of the swatches is measured with an EEL Spectrophotometer (Evans-Electro-selenium Ltd. UK) with filter number 603. The light reflectance is measured on the swatches before (X) and after (Y) soaking and/or washing treatment and the percent stain removal (R%) is calculated using the following formula:

$$R\% = \frac{Y - X}{100 - X} \cdot 100$$

Stained swatches were soaked according to procedure B using detergent composition (b) containing cysteine as activator. The reflectance readings show very clearly the cleaning synergism obtained by incorporating an activator into an enzyme containing detergent composition.

TABLE I

Staining solution used	Stain removal (R%)		
	Without activator	1% of cysteine	3% of cysteine
Blood-milk-ink	10.5	16.0	18.5
Milk-ink	28.5	42.0	40.0
Egg-white-ink	5.0	17.5	27.5
Cocoa	10.0	14.5	16.0

Stained swatches were washed in a Terg-O-Tometer according to procedure A using detergent composition (a) containing cysteine as activator.

TABLE II

Staining solution used	Stain removal (R%)	
	Without activator	3% of cysteine
Egg-white-ink	25	32
Blood	15	21
Blood-milk-ink	21	26

Any of the following examples has been carried out by washing with egg-white-ink swatches according to procedure A.

The detergent formulation used corresponds to (a) of example I wherein the quantities of enzyme preparation have been varied as indicated.

TABLE III

Example	Activator	Wt. percent of activator	Wt. percent of ALCALASE (same as in Example I)	Stain removal (R%)	
				Without activator	With activator

We claim:

1. An enzyme-containing detergent composition consisting essentially of an organic detergent and an alkaline builder salt in a ratio of builder salt to detergent of about 20:1 to 1:5; from about 0.01 to about 10 weight percent of the composition

of an enzyme activity-enhancing agent containing one or more sulphydryl groups and selected from the group consisting of cysteine, cysteine hydrochloride, thioglycollic acid, thioglycerol, thioglycolic acid esters of alcohols containing from one to about 16 carbon atoms, thioglycolic acid ethylester, and calcium thioglycolate; and from about 0.005 to about 4 weight percent of a proteolytic enzyme which does not contain sulphydryl groups or disulfide bonds.

2. The detergent composition of claim 1 wherein the enzyme used is of bacterial origin.

3. The detergent composition of claim 2 wherein the enzyme used is obtained from a strain of *bacillus subtilis*.

4. The detergent composition of claim 1 wherein the enzyme is present in an amount of from about 0.01 to about 0.2 weight percent.

5. The detergent composition of claim 1 wherein the sulfhydryl bearing compound is present in an amount of from 0.05 to 5 weight percent.

6. The detergent composition of claim 5 wherein the sulfhydryl bearing compound is present in an amount of from about 0.2 to about 2 weight percent.

7. The composition of claim 6 wherein the sulphydryl bearing compound is cysteine.
